ASSIGNORS TO CHICAGO PNEUMATIC TOOL COMPANY, OF CHICAGO, ILLINOIS, A
CORPORATION OF NEW JERSEY.

UNLOADER FOR AIR-COMPRESSORS.

1,224,272.

Specification of Letters Patent.

Patented May 1, 1917.

Application filed March 8, 1915. Serial No. 12,928.

To all whom it may concern:

Be it known that we, WILLIAM H. CALLAN and GEORGE J. MACFADDEN, citizens of the United States, residing at Franklin, in the county of Venango and State of Pennsylvania; have invented certain new and useful Improvements in Unloaders for Air-Compressors, of which the following is a specification.

10 Our invention relates to an unloader for air compressors and the object thereof is to provide a simple, efficient and reliable device of this kind, which is characterized more particularly by the employment of a 15 valve provided with two separate seats for controlling openings of differential area for the loaded and unloaded position of the valve with the result that the valve is positive in its action in both opening and closing, there being no position or condition of 20 hesitation of the valve between opening and closing positions. In prior devices when a certain point is reached in their operation at which time the supply and the demand 25 become substantially equal, they will hesitate between loading and unloading consequently giving great trouble and annoyance, whereas in our device there being two different areas exposed in the two positions, 30 there is no possible chance for hesitation between loading and unloading and the valve will therefore move positively against one seat or the other at all times. Other features of novelty and utility in my unloader, 35 will be apparent from the description hereinafter given.

In the drawings Figure 1 is an elevation of a part of a compressor showing an inlet valve and our unloader in section; Fig. 2 a 40 central longitudinal section of the unloader on a larger scale than shown in Fig. 1 and illustrating the valve in unloaded position; Fig. 3 a central longitudinal section of a modified form of unloader illustrating the 45 valve in loaded position; Fig. 4 a top plan view of the valve of Fig. 3 and Fig. 5 a central longitudinal section of one end of another modified form of unloader.

Our invention may be embodied in structures of somewhat different form and arrangement and in the present instance we have illustrated three different forms, all of which have substantially the same mode of operation and accomplish the same result.

Referring to the embodiment of our invention as illustrated in Figs. 1 and 2 the unloader comprises a shell or casing of suitable form and dimensions and inclosing the unloader valve which is adapted to control the admission of the air pressure from the receiver or the like to a fluid pressure controlled mechanism acting on some part of the air compressor such as the suction valve for holding the latter from its seat and permitting the compressor to run or operate 55 without compressor. In the present instance the unloader consists of a shell or casing 1 having at its upper end (assuming that the unloader is placed in a vertical position) a chamber 2 and at its lower end a 70 chamber 3, the former being of the larger diameter. The upper end of the chamber 2 is closed by a hollow screw plug or cap 4 having an interior pressure chamber 5 in which the receiver pressure is always present inasmuch as such chamber communicates therewith through the pipe 6 leading from the receiver through the top of the cap.

A seat 7 is formed in the chamber 2 at the junction thereof with the other chamber 3 80 and another seat 8 is formed at the lower end of the cap 4. Both of these seats are circular and the seat 7 is somewhat larger in diameter than the other seat for the purpose and with the result hereinafter explained. 85 The unloader valve 9 is in the form of a plate or disk whose opposite faces form seats adapted to cooperate with the seats 7 and 8, the valve being upon one seat in the unloaded and on the other in the loaded position thereof.

Referring to the particular construction shown in Figs. 1 and 2, the unloading valve is mounted to slide upon the exterior walls of the cap 4 and to this end the valve is provided with marginal flanges 10 which surround said walls and are guided thereby in the vertical movements of the valve. This flange is provided with one or a series of openings or ports 11 through which the air 100 from the receiver passes into chamber 2 when the valve is in open or unloaded position as indicated in Fig. 2, the air first passing from the chamber 5 past the valve seat 8 and through the circumferential groove 12 before passing through the ports 11.

The unloading valve is held to its loaded or working position shown in Fig. 1 with a

predetermined pressure by means of a plunger 13 whose head or upper end has a point bearing contact with the under side of the unloader valve. This plunger is spring-
5 pressed upwardly by means of the coiled spring 14 whose upper end bears against the head of the plunger and whose lower end bears against a washer 15 which in turn bears against the inner end of the adjusting screw 16 which screws into the lower end of the casing 1. The tension of the spring can be regulated or adjusted by screwing the screw 16 in or out accordingly as required, the same being held in adjusted position by
10 means of the jam nut 17. The adjusting screw is hollow in order to receive the plunger 13 and thereby serve as a guide therefor.

The chamber 2 is connected by means of the pipe connection 18 to fluid pressure operated mechanism which in the present instance act upon the suction or inlet valves respectively, one of which together with said mechanism is shown in section in Fig. 1. This mechanism consists of a piston 19 operating in a chamber or cylinder formed in a block or plug 20 screwing into the upper end of the casing 21 of the inlet valve, the cylinder proper communicating with the chamber 22 formed by a cap 23 screwing onto the block 20. A branch pipe 24 leads from the pipe 18 through the cap 23 to the chamber 22 to admit the air pressure against the piston 19 to force the latter downwardly. A similar branch pipe 24 leads to the other suction valve structure as shown in Fig. 1.

The piston 19 acts against a series of depending arms 25 which when moved downwardly by the piston bear against the suction valve 26 holding it open as long as the piston 19 is acted upon by the air pressure. As a result the compressor will operate without compression inasmuch as the air will blow in and out through the inlet openings during the reciprocations of the piston 45 (not shown) of the compressor.

When the pressure in the receiver has reached a predetermined degree such pressure which is always present in the chamber 5 acts to move the valve 9 from its inner seat 8 by overcoming the resistance of the spring 14 and to seat it on its outer seat 7. The air will thereupon flow from chamber 5 through the ports 11 to the chamber 2 from whence it passes from the pipes 18 and 24 to 55 the chamber 22. The piston 19 will now be forced downwardly and the inlet valve 26 will be held open. This represents the unloaded position of the parts.

When the pressure in the receiver and 60 pipe connection 6 have been reduced to a certain predetermined degree the spring 14 will overcome the pressure exerted on the top of the valve and will raise it from its seat 7 and seat it upon the other seat 8. The air which would otherwise be trapped

in the pipes 18 and 24 and the chamber 22 will now be released therefrom by flowing from the chamber 2 past the seat 7, through the chamber 3 and out through the outlet ports 27 in the casing 1. This represents 70 the normal or loaded position of the parts. It will be understood that when the pressure is thus exhausted through the ports 27 the fluid pressure mechanism is of course relieved and restored to normal position by 75 means of the coiled spring 28 acting to raise the piston 19 and its connected parts to normal position shown in Fig. 1, thereby removing the interference with the functions of the inlet valve.

The diameter of the seat 8 is somewhat less than the other seat 7 with the result that the unloading valve when unloaded is unbalanced to the extent of the difference in the areas less the added tension of the 85 spring 14 when the valve is on the seat 7, with the result that the valve is held tightly upon such latter seat until the pressure from the receiver, that is the pressure exerted upon the top area of the valve is 90 reduced to a definite point whereupon the tension of the spring overcomes said pressure, unseating the valve at the seat 7 and seating it upon the other seat 8 as above explained.

The inner end of the cap is in the form of a tubular extension which not only forms the seat 8 as described but also forms a means for guiding the valve in co-operation with its marginal flange. The construction is such that the ports 11 are always open. In the present instance the seat 8 is formed by cutting away the outer corner of the inner end of said tubular extension leaving the seat 8 projecting so as to be contacted by the top face of the valve.

Referring to the modification shown in Figs. 3 and 4, the main parts are the same with the exception that the valve is guided both on the outside and inside of the tubular extension of the cap but mostly on the inside inasmuch as the marginal flange 10' of the valve is shorter than the flange 10 of the form shown in Figs. 1 and 2. To provide for the inside guide the valve is 115 provided with an upwardly-extending tubular portion 9" having a series of radial ribs 9" adapted to fit and slide on the inner walls of the tubular extension of the cap 4. In addition the plunger 13 has the portion 13" extending through the valve and into the hollow tubular extension 9" of the valve. In other respects the construction is substantially the same as that shown in Fig. 2.

In Fig. 5 we have shown still another 125 modified form of construction which is similar to that of Fig. 2 with the exception that the plunger 13 is dispensed with and a tubular extension 29 is formed on or secured to the under side of the valve adapted to slide 130

- in the chamber 3 to assist in guiding the valve in connection with the upwardly-extending flange 10 of the valve. Moreover in this instance the spring 30 bears directly against the valve. The tubular extension 29 is provided with one or more ports or passages 31 for permitting the exhaust of the air from the fluid pressure operated mechanism when the valve is on its seat 8.
10. While in the drawings we have shown the unloading valve covering the two suction valves of the same cylinder it will be understood that this valve may be utilized to control all of the suction valves of a multistage compressor by providing the fluid pressure operated mechanisms for actuating the suction valves of the other cylinders and by connecting such mechanisms with the pipe 18.
20. We claim:
1. A controlling device for air compressors comprising a casing adapted to communicate respectively with a supply of air under pressure and with a fluid pressure operated unloader mechanism, said casing also having an outlet to atmosphere, two opposed seats in said casing, one of which communicates with said supply and the other with said outlet, a valve influenced constantly by a predetermined pressure and operating between said seats and adapted to be seated upon one seat or the other, and means beyond the valve seat communicating with the air supply for throttling the passage from said seat.
  35. 2. In a device of the class described, the combination of a casing having opposed valve seats therein, a valve movable between and adapted to engage said seats, a connection from one of said seats to an air receiver, connections from the other said seat to exhaust, a connection from said casing to a fluid pressure actuated unloader mechanism and means beyond said valve seat for throttling the air coming from the receiver.
  45. 3. A controlling device for air compressors comprising a casing, a connection from said casing to a receiver, a valve seat controlling said connection, an outlet opening from the casing to the atmosphere, a valve seat controlling said outlet, a connection from said casing to a fluid pressure operated unloader mechanism, a valve cooperating with said valve seats to alternately close the connection from the receiver and the outlet respectively to said fluid operated unloader mechanism and means cooperating with the valve and the first said valve seat to throttle the flow of air from the receiver to the interior of the casing.
  60. 4. A controlling device for air compressors comprising a casing having a tubular portion communicating with a receiver and formed at one end with a valve seat, a connection from said casing to a fluid pressure operated unloader mechanism, said casing
  65. also having an outlet to the atmosphere, a second valve seat opposite the first said seat, a valve arranged between said seats and adapted to cooperate with the same alternately, means for exerting a predetermined pressure upon the valve to normally hold it upon the first said seat, said valve having a sliding engagement with said tubular portion of the casing whereby the air passing from the receiver through the first said valve seat is throttled.
  5. A controlling device for air compressors comprising a casing having a connection for a fluid pressure unloader mechanism, a connection from said casing to a receiver, a valve seat controlling the latter connection, the casing also having an outlet to the atmosphere and a valve seat controlling said outlet, the two valve seats being in opposed positions, a valve cooperating with the valve seats to alternately close the same, a flange on the valve having a sliding connection with the first said valve seat and openings in the flange of smaller total capacity than the opening in the valve seat whereby the flow of air through the seat is throttled.
  6. A controlling device for air compressors comprising a casing adapted to communicate respectively with a supply of air under pressure and with a fluid pressure operated unloader mechanism, said casing also having an outlet to the atmosphere, two opposed seats in said casing, one of which communicates with said supply and the other with said outlet, the former being of less area than the other, a valve cooperating alternatively with the two valve seats, and means for forcing such valve against the seat communicating with the air supply and passages arranged to communicate with the valve seat communicating with the supply when said seat is open, of restricted total area compared to said seat.
  7. A controlling device for air compressors comprising a casing having a tubular portion communicating with a source of air under pressure and provided at one end with a valve seat, said casing also having a communication with a fluid pressure operated unloader mechanism and an outlet to the atmosphere, a second seat larger than the first named seat and arranged opposite thereto and between said communication and said outlet, a valve arranged between said seats and adapted to be seated upon one seat or the other, and means for exerting a predetermined pressure upon the valve to normally hold it upon said smaller seat, said valve being of a diameter greater than that of said smaller seat, said valve being mounted to slide upon and be guided by said tubular portion.
  8. A controlling device for air compressors comprising a casing having a tubular portion communicating with a source of air

under pressure and provided at one end with a valve seat, said casing also having a communication with a fluid pressure operated unloader mechanism and an outlet to the atmosphere, a second seat larger than the first named seat and arranged opposite thereto and between said communication and said outlet, a valve arranged between said seats and adapted to be seated upon one seat or the other, and means for exerting a predetermined pressure upon the valve to normally hold it upon said smaller seat, 5 said valve being of substantially disk form with a marginal flange sliding upon the outer walls of said tubular portion and with a circular groove between its seat and the flange.

10 one seat or the other, and means for exerting a predetermined pressure upon the valve to normally hold it upon said smaller seat,

said valve being of substantially disk form with a marginal flange sliding upon the

15 outer walls of said tubular portion.

9. A controlling device for air compressors comprising a casing having a tubular portion communicating with a source of air under pressure and provided at one end 20 with a valve seat, said casing also having a communication with a fluid pressure operated unloader mechanism and an outlet to the atmosphere, a second seat larger than the first named seat and arranged opposite thereto and between said communication and said outlet, a valve arranged between said seats and adapted to be seated upon one seat or the other, and means for exerting a predetermined pressure upon the valve to normally hold it upon said smaller seat, 25 said valve being of substantially disk form with a marginal flange sliding upon the outer walls of said tubular portion and having a passage for the air controlled by the

30 valve.

10. A controlling device for air compressors comprising a casing having a tubular portion communicating with a source of air under pressure and provided at one end with 35 a valve seat, said casing also having a communication with a fluid pressure operated unloader mechanism and an outlet to the atmosphere, a second seat larger than the first named seat and arranged opposite thereto and between said communication and said outlet, a valve arranged between said seats and adapted to be seated upon

one seat or the other, and means for exerting a predetermined pressure upon the valve to normally hold it upon said smaller seat, 50 said valve being of substantially disk form with a marginal flange sliding upon the outer walls of said tubular portion and with a circular groove between its seat and the flange.

55

11. A controlling device for air compressors comprising a shell having an open end, a cap removably secured to the shell having a tubular portion extending into the shell and communicating with a source of air 60 under pressure, the inner end of said tubular portion providing a valve seat, said shell also having communication with a fluid pressure operated unloader mechanism and an outlet to the atmosphere, said shell having a seat arranged opposite the other seat and between said communication and said outlet, the latter seat being the larger, and a valve arranged between and coöperating with said seats and normally held upon the 65 smaller seat with a predetermined yielding pressure, said valve having a cylindrical marginal flange sliding upon the outer wall of said tubular portion, and formed with openings therein.

65

70 12. A controlling device for air compressors comprising a casing 1 having chambers 2 and 3 and outlet port 27 and also having a seat 7, a cap 4 removably secured to said casing and having a tubular portion extending into chamber 2, the inner end of which provides a seat 8 smaller than seat 7, and an unloader valve 9 of disk form arranged between the two seats and coöperating with both of them, said valve being 75 provided with a marginal flange 10 sliding on said tubular extension and having ports 11 closed when the valve is on seat 8 and opened when the valve is on seat 7.
